UNITED STATES PATENT OFFICE.

AUGUST J. DINKLAGE, OF EAST ORANGE, NEW JERSEY.

DEVICE FOR PREVENTING CREEPING OF RAILS.

1,153,541.

Specification of Letters Patent. Patented Sept. 14, 1915.

Application filed February 27, 1915. Serial No. 10,919.

To all whom it may concern:

Be it known that I, AUGUST J. DINKLAGE, a citizen of the United States, and resident of East Orange, county of Essex, and State of New Jersey, have invented a certain new and useful Improvement in Devices for Preventing Creeping of Rails, of which the following is a specification.

My invention relates to devices for preventing longitudinal creeping of railroad rails and the like and has for its object to provide a simple device of this character which is readily combined with the rail and operates with a maximum of efficiency and which in addition serves to secure the rail upon the tie or sleeper.

My improvement will be fully described hereinafter and the features of novelty will be pointed out in the appended claims.

An example of my invention and its application is shown in the accompanying drawings in which—

Figure 1 is a plan view; Fig. 2 is a cross-section on the line 2—2 of Fig. 1; and Fig. 3 is a side view of one of the elements of my device.

In the drawings 5 represents the rail having the usual rail base 6 resting either directly upon the sleepers or ties 7 or upon the tie plates 8 located thereon. The means for securing the rail in position on the ties which at the same time comprises the device for preventing longitudinal creeping thereof consists of screw spikes 9 having the customary heads 10 and angular projections 11 for the accommodation of a wrench or other tool whereby said spikes are screwed into the tie 7, the tie plate 8 if used being provided with apertures 8^a through which said spikes extend. The shank or stem of each screw spike 9 is provided, at a point preferably just below the head 10 with teeth or serrations 12 adapted in the operative condition of the parts to mesh with similar teeth or serrations 13 formed on a member 14 depending from a wedge plate 15 having a wedging surface 16 as shown in Fig. 3. When the parts of the device are operatively assembled, the said wedge plate has its wedging surface 16 in surface engagement with the upper surface of the rail base 6 and the depending member 14 in contact with the side edge thereof as shown in Fig. 2. The said wedge plate 15 is thus located between the head 10 and the rail base 6 while the depending member 14 is positioned between

the said base and the stem or shank of the spike 9, it being understood that the wedge plate 15 and depending member 14 are integral with and extend at approximately 60 right angles to each other in cross-section.

In assembling the parts the wedge plate 15 is inserted between the rail base 6 and the head 10 before the spike 9 has been driven fully home, the small end *a* of the wedge plate pointing in the direction in which the rail tends to creep and the depending member 14 being in engagement with the side edge of said base 6 with the teeth 13 near the end *a* in mesh with the teeth 12 of the spike 9. The latter is then rotated and driven fully home, this operation through the medium of the intermeshing teeth 12 and 13 moving the plate 15 and members 14 lengthwise of the rail base to approximately 75 the position shown in Fig. 1 or until the head 10 rests upon the wedge member 15 as illustrated in Fig. 2. In the illustration the tendency of the rail 5 is to creep in the direction indicated by the arrow in Fig. 1, 80 the small end *a* of the wedge plates located on the right hand side of the rail base when looking in the direction of the arrow, accordingly pointing in this direction.

Any tendency of the rail to creep, after 85 the devices are in operative position will carry along all the wedge plates 15 and members 14 located on said right hand side of the rail and will thus force said wedges more firmly beneath the heads 10 of the 90 spikes 9. At the same time the corresponding movement of the member 14 will, through the medium of the teeth 12 and 13 rotate the spikes 9 about their axis in a clockwise direction to screw said spikes farther into the ties 7. A double clamping action is in this manner secured; that is the wedge members 15 are driven more firmly beneath the heads 10 owing to the action of the surface 16 on the rail base and the heads 10 themselves are forced down into firmer contact with said wedge plates 15 by reason of the rotation of the spikes as above mentioned. The rail base is thus securely and automatically clamped and the creeping tendency of the rail is immediately checked. If the devices are also located at the opposite or left hand edge of the rail base which need be the case only in single track roads in which the traffic in both directions is over the same rails, the ends *a* of the wedge plates at this opposite edge point in the 100 105 110

direction opposite to that of the wedge plates located on the right hand side of said rail. These latter wedge plates and connected parts at the left hand edge are not affected during the operation as above described, the rail base merely moving relatively thereto when the traffic is as indicated by the arrow in Fig. 1. When the traffic is in the opposite direction the operation is the same as hereinbefore described, the devices at the right hand edge being inactive during this latter operation. It will of course be understood that in double track roads the described devices need only be located so as to be operated by the creeping tendency of the rail in whatever direction this may be, ordinary screws or other spikes serving to secure the opposite edges of the rail bases to the ties or sleepers.

It will be seen that my device provides a simple structure which not only efficiently prevents creeping of the rails either in single or double track roads but also serves to secure the rails to the ties in a maximumly effective manner. In other words the vibration which ordinarily tends to loosen the spikes will in the present case serve to tighten the same more effectively.

The device is simple in construction and easy of application and may be incorporated in existing roads without disturbing same.

Various changes in the specific form shown and described may be made within the scope of the claims without departing from the spirit of my invention.

I claim:

1. The combination of a rail having a base, a screw spike adapted to secure said rail in position and means interposed between said spike and rail base whereby said spike is rotated and tightened by the creeping action of the rail and said creeping is checked.

2. The combination of a rail having a

base, a screw spike adapted to secure said rail in position, a head on said spike, and means adapted to be wedged beneath said head and to rotate and tighten said spike by the creeping action of the rail whereby said creeping is checked.

3. The combination of a rail having a base, a screw spike adapted to secure said rail in position, a head on said spike, a wedge located between said head and the rail base and a connection between said screw spike and the wedge whereby the latter is jammed beneath said head and the spike is rotated to jam said head upon said wedge by the creeping action of the rail and said creeping is checked.

4. The combination of a rail having a base, a wedge resting upon said base, a member depending from the outer edge of said wedge and engaging the edge of said base, a screw spike adapted to secure said rail in position, a head on said spike adapted to bear on said wedge and coöperating teeth on said depending wedge member and said spike whereby the wedge is jammed beneath said head and the spike is rotated to jam said head against said wedge by the creeping action of the rail and said creeping is checked.

5. An anti-creeping device for railroad rails comprising a wedge provided with teeth and a screw spike provided with teeth arranged to mesh with the teeth of said wedge, said wedge and spike being operated one by the other to check a creeping movement of the rail.

In testimony whereof I have hereunto set my hand in the presence of two subscribing witnesses.

AUGUST J. DINKLAGE.
